UNITED STATES PATENT OFFICE.

ALFRED A. ZIEGLER, OF BOSTON, MASSACHUSETTS.

RAILWAY SIGNAL-LANTERN.

1,082,577.

Specification of Letters Patent.

Patented Dec. 30, 1913.

Original application filed June 6, 1912, Serial No. 701,978. Divided and this application filed January 8, 1913. Serial No. 740,773.

To all whom it may concern:

Be it known that I, ALFRED A. ZIEGLER, a citizen of the United States, residing at Boston, in the county of Suffolk and State of 5 Massachusetts, have invented an Improvement in Railway Signal-Lanterns, of which the following is a specification.

This application is a division of my application #701,978, filed June 6, 1912.

10 The invention relates to railway signal-lanterns employing incandescent electric-lamps, and has for its object the provision of a base-plate for the lamps having electric contact-members thereon, which is adapted 15 to be removably placed in the lantern-body by a sliding movement and said contact-members to engage electric contact-members arranged in the lantern-body whereby the 20 circuit for the lamps is established, said base-plate being so constructed that when arranged in the lantern-body it will be properly localized to insure engagement of the contact-members.

Two incandescent electric-lamps may be 25 arranged on the base-plate and an automatic circuit-controller provided for including the second lamp in circuit in case the first lamp burns out, but so far as my invention is concerned the construction of the lamps and 30 the provision of an automatic circuit-controller therefor are not material.

Figure 1 is a front elevation of a railway signal-lantern embodying this invention, the door being raised to expose the electric-lamps and the removable base-plate arranged therein. Fig. 2 is a plan view of the base-plate and the electric connections by which the lamps are connected with the supply-wires. Fig. 3 is a transverse section 10 of the base-plate taken on the dotted line 3-3, Fig. 2. Fig. 4 is a side elevation of a portion of the base-plate. Fig. 5 is a side elevation of one of the blocks to which the circuit-wires are attached. Fig. 6 is a modified form of base-plate for the lamps and the electric connections.

a represents the base-plate for the lamps, which is adapted to be removably arranged in the lantern-body *a'*, and *b'*, *c'* electric-lamps arranged on said base-plate, one or more of which may be employed. *d* is an electro-magnet arranged on the base-plate and *d'* its armature, which controls a switch by which the second lamp is turned on in case the first lamp burns out, substantially as represented in my aforesaid application. Said base-plate *a* is designed to be removably placed in the lantern-body, by a sliding movement, so that it can be easily inserted and withdrawn, and suitable electric connections are provided whereby, when inserted, the lamps which are arranged thereon will be connected with the supply wires. As here shown, said base-plate has arranged upon opposite sides of it resilient arms *a²*, *a³*, the arm *a²* being connected with the plate *f'* on the base-plate, and the arm *a³* being connected with the plate *f* on the base-plate, said arms constituting electric contact-members. In the body of the lantern, at 60 opposite sides thereof, two blocks of insulating material *a⁵* and *a⁶* are arranged, having binding-posts *a⁷* and *a⁸* to which the supply wires are connected and having contact-plates *a⁹* and *a¹⁰* extended down along the 65 adjacent sides of the blocks for engagement therewith of the resilient contact-members *a²*, *a³*. The adjacent sides of said blocks *a⁵*, *a⁶*, are formed each with a longitudinal groove extended from end to end of it, and 70 said grooves serve as guides to receive the resilient contact-members *a²*, *a³*, as the base-plate is inserted between the blocks to thereby guide the movement of the base-plate.

When the base-plate is slid into place 85 electric connections with the supply-wires are established, but it must be correctly localized so that the contact-members *a²*, *a³*, will engage respectively the contact-plates *a⁹*, *a¹⁰*. To provide for thus localizing the 90 base-plate it is made of a length to substantially fit the interior of the lantern-body, so that when its rear end strikes against the wall of said body its front end will occupy a position just inside said body to admit of 95 closing of the door, as represented in Fig. 2. Localizing the base-plate to insure engagement of the electric connections is of importance for the reason that many of these lanterns are in charge of persons unskilled 100 in electric construction, hence it is necessary to provide for the engagement of the electric connections by means entirely outside of or beyond their control. In lieu of the form of block thus described the form shown 105 in Fig. 6 may be employed wherein a single block *a²⁰* of insulating material is arranged at the back of the lantern-body, having a pair of contact-members *a²¹*, *a²¹*, attached to binding-posts *a²²*, *a²²*, and the removable 110

base-plate has contact-members at its inner end adapted to engage said contact-members a^{21} , a^{21} , and the supply-wires are connected to said binding-posts a^{22} , a^{22} . In this instance the base-plate is simply slid into and out of the lantern and when inserted electric connections are established with the supply-wires. Other forms of electric connections may be employed, arranged on the sliding base-plate for the lamps.

I claim:—

1. A railway signal-lantern comprising a lantern-body having provision for localizing a removable sliding base-plate and having stationarily supported electric contact-members and means for electrically connecting supply-wires thereto, and a removable sliding base-plate bearing an incandescent lamp adapted for localization in said lantern-body, electric contact-members arranged on said base-plate, electrically connected with the lamp and adapted for engagement with the contact-members in the lantern-body when the base-plate bearing them is correctly localized in said lantern-body, substantially as described.

2. A railway signal-lantern comprising a lantern-body, side guides for a removable sliding base-plate having stationarily supported electric contact-members and means for electrically connecting supply wires thereto, and a removable sliding base-plate made of a length to substantially fit the interior of the lantern-body when the door thereof is closed, said base-plate bearing an incandescent lamp, electric contact-members arranged on said base-plate, electrically connected with the lamp and adapted for engagement with the contact-members in the lantern-body when the base-plate is slid into said body far enough to admit of closing the door, substantially as described.

3. A railway signal-lantern comprising a

lantern-body having provision for localizing a removable sliding base-plate, side guides for said base-plate, stationarily supported electric contact-members arranged on said guides, and means for electrically connecting supply wires thereto, a removable sliding base-plate bearing an incandescent lamp adapted for localization in said lantern-body, and electric contact-members arranged on said base-plate electrically connected with the lamp and adapted for engagement with the contact-members on the side guides when the base-plate is correctly localized in the lantern-body, substantially as described.

4. A railway signal-lantern comprising a lantern-body having provision for localizing a removable sliding base-plate, side guides for said base-plate having grooves in their adjacent sides, stationarily supported electric contact-members arranged on said side guides and extended across the grooves therein, and means for electrically connecting supply-wires thereto, a removable sliding base-plate bearing an incandescent lamp adapted for localization in said lantern-body, and electric contact-members arranged on the sides of said base-plate which are electrically connected with the lamp, said contact-members being extended outward and adapted to enter the grooves in the side guides and engage the contact-members therein when the base-plate is correctly localized in the lantern-body, substantially as described.

In testimony whereof, I have signed my name to this specification in the presence of two subscribing witnesses.

ALFRED A. ZIEGLER.
